UNITED STATES PATENT OFFICE.

MANUEL HUMBERTO PÉREZ, OF SAN PEDRO SULA, HONDURAS.

INTERNAL-COMBUSTION MOTOR.

Application filed November 20, 1923. Serial No. 675,926.

To all whom it may concern:

Be it known that I, MANUEL HUMBERTO PÉREZ, a citizen of the Republic of Honduras, residing at San Pedro Sula, in the Department of Cortez and Republic of Honduras, have invented new and useful Improvements in Internal-Combustion Motors, of which the following is a specification.

This invention relates to improvements 10 in motors of the internal combustion type, and particularly to motors in which the working pistons operate in pairs and are so arranged and timed in action as to deliver their working impulses so as to maintain a continuity of motion and avoid dead centers.

The object of the invention is to provide novel means for transmitting the working impulses of sets of pistons to an element 20 to be driven, and for regulating the speed of the part to be driven as may be desired.

With these and other objects in view, the invention consists of the features of construction, combination and arrangement of 25 parts, hereinafter fully described and claimed, reference being had to the accompanying drawings, in which:—

Figure 1 is a vertical longitudinal section through the motor on the line $x-x$ of 30 Figure 2.

Figure 2 is a horizontal section through the motor on the line $y-y$ of Figure 1.

The motor in the form shown comprises an enclosing casing 1 divided on a horizontal line to provide upper and lower casing sections 2 and 3 united by bolts or other suitable fastenings 4. The bottom casing section 3 and base of the top casing section 2 form a crank casing or chamber 5 closed 35 by an integral bottom head 6. A detachable head 7 closes the top of the casing section 2, and forms with an underlying partition 8 a water jacket space 9, which in practice may be connected in the usual or preferred 40 manner with any ordinary type of radiator.

In practice the motor may be equipped 45 with any desired number of cylinders and pistons, arranged in working pairs, the cylinders of each pair being disposed in parallel relation for working coaction with each other. The motor disclosed is designed 50 to be provided with four cylinders 11 and cooperating pistons 12, arranged in working pairs on opposite sides of the longitudinal center of the engine, one pair of working cylinders and pistons only located at one side

of the engine being shown, it being understood that such arrangement in practice is duplicated at the opposite side of the engine, each pair of pistons being operatively arranged to transmit working motion through connecting rods 33 to a crank shaft 18. As shown clearly in Figure 2, the two crank shafts 18 are arranged in parallel relation and extend longitudinally of the 60 crank casing 5 and are journaled in bearings between the opposed surfaces of the casing sections 2 and 3. Each crank shaft has keyed thereto at one end a gear element 19 embodying relatively small and large gears 70 20 and 21 meshing respectively with comparatively large and small transmission gears 22 and 23 rotating about a stationary shaft 24 and suitably journaled on the engine casing and on said driven shaft. Loosely 75 mounted to slide and rotate upon shaft 24 is a sleeve or hollow shaft 25 carrying a friction cone or gear 26 slidably movable in opposite directions to engage cone surfaces on the gear members 22 and 23, 80 whereby a change speed gearing is provided adjustable for driving a driven or power transmitting shaft 24' at different speeds from the shafts 18, and for also ensuring the revolution of the shafts 18 at the same 85 speed so as to properly time the working motions of the pistons. Sleeve 25 is feathered to shaft 24' to slide thereon and rotate therewith. Any suitable type of shifting means may be coupled to the sleeve 25 90 for the purpose of adjusting the same back and forth for a change speed action, such as a conventional type of shifter fragmentarily shown at 24" in Figure 3.

Having thus fully described my invention, 95 I claim:

1. A motor comprising a casing, sets of cylinders on opposite sides of the center of the casing, pistons operating in said cylinders, shafts on opposite sides of the 100 center of the casing and driven respectively by the respective sets of pistons, high and low speed gears carried by said shafts, a driven shaft having a gear thereon, and intermediate loose gears meshing with the 105 high and low speed gears on the respective piston driven shafts and adapted to be fixed for engagement with the gear on the driven shaft, and means for adjusting the driven shaft to move the gear thereon into or out 110 of engagement with the high or low speed loose gears.

2. A motor comprising a main casing, a transverse gear casing at one side thereof, sets of aligned cylinders on each side of the center of the main casing, pistons working in said cylinders, a crank shaft for each set of pistons and to which the pistons are coupled, said shafts being journaled in the main casing and having extended end portions extending into the gear casing and journaled therein, a driven shaft journaled in the gear casing between and parallel with the extended end portions of the crank shafts, high and low speed gears fixed to

the extended ends of the crank shaft, coacting high and low speed gears loose on said driven shaft, a hollow shaft of sleeve slideable on and rotatable with the driven shaft and through one of the latter named gears, a clutch carried by said hollow sleeve or shaft and movable thereby to engage either of the gears on the driven shaft to fix the same to the driven shaft, and means for shifting said hollow sleeve or shaft.

In testimony whereof I affix my signature.

MANUEL HUMBERTO PÉREZ.
